UNITED STATES PATENT OFFICE.

HENRY JOSEPH, OF GRAYLING, MICHIGAN, ASSIGNEE TO JOSEPH SANITARY PRODUCTS COMPANY, OF MILWAUKEE, WISCONSIN, A CORPORATION OF WISCONSIN.

DESIGN FOR A RUBBER MAT AND COVER.

59,966.

Specification for Design.

Patented Dec. 13, 1921.

Application filed November 10, 1920. Serial No. 423,195. Term of patent 14 years.

To all whom it may concern:

Be it known that I, HENRY JOSEPH, a citizen of the United States, residing in the city of Grayling, in the county of Crawford and State of Michigan, have invented a new, original, and ornamental Design for Rubber Mats and Covers, of which the following is a specification, reference being had to the accompanying drawing, forming part hereof.

In the drawing, Figure 1 shows a plan view of my improved design for rubber mats and covers, in which the surface is ornamented by the simulation of a textile fabric, in which the crossing of the warp and weft threads is sharply delineated, together with the interstices at such crossings. Fig. 2 shows an edge view of a section of the new mat or cover.

I claim:

The ornamental design for a rubber mat and cover, as shown.

In testimony whereof, I have signed my name at Milwaukee, Wisconsin, this 8th day of November, 1920.

HENRY JOSEPH.
